UNITED STATES PATENT OFFICE.

JOSEPH BREGMAN, OF SOUTH BROOKLYN, NEW YORK.

DESIGN FOR AN OVERGAITER.

53,983.

Specification for Design.

Patented Nov. 4, 1919.

Application filed January 23, 1918. Serial No. 213,421. Term of patent 14 years.

To all whom it may concern:

Be it known that I, JOSEPH BREGMAN, a citizen of the United States, residing at South Brooklyn, county of Kings, State of New York, have invented a new, original, and ornamental Design for Overgaiters, of which the following is a specification, reference being had to the accompanying drawing, forming part thereof.

Fig. 2 is a rear end elevation.

I claim:

The ornamental design for an overgaiter, as shown.

JOSEPH BREGMAN.

Witnesses:

HENRY J. LUCKE,
SOPHIE M. BAEDER.
